UNITED STATES PATENT OFFICE.

ROBERT D. H. ANDERSON, OF CINCINNATI, OHIO, ASSIGNOR OF ONE-HALF TO WALTER R. ROCKHOLD, OF CINCINNATI, OHIO.

INCANDESCENT-LAMP HANGER.

1,077,663.

Specification of Letters Patent.

Patented Nov. 4, 1913.

Application filed March 26, 1910. Serial No. 551,667.

To all whom it may concern:

Be it known that I, ROBERT D. H. ANDERSON, a citizen of the United States of America, and a resident of Cincinnati, in the 5 county of Hamilton and State of Ohio, have invented a certain new and useful Improvement in Incandescent-Lamp Hangers, of which the following is a specification.

This invention relates to incandescent 10 electric-lamp holders and particularly to those of the type adapted for use in supporting a lamp at the desired angle to suit the position of the work in the process of the manufacture of goods or for any other 15 use to which such a lamp could be put to the best advantage for the convenience of the person or operator.

The object of the invention is to provide 20 simple and effective means for producing the above-noted result, the details of such means being hereinafter fully described and particularly pointed out in the claims.

In the accompanying several sheets of 25 drawings, forming a part of this specification, Figure 1 is an elevation of my invention, showing, in dotted-lines, the lamp extended from the holder perpendicularly, the said lamp and its clamp being further shown in projected dotted-lines (to the right) to 30 indicate how the lamp can be swung or turned half-way around horizontally and, also, how the said lamp can be swung or turned to bring it to a horizontal position at a right-angle to the vertical one; Fig. 2, 35 a detail elevation of the improved disk angling-joint device at the top of the holder, shown at right-angles to that seen in Fig. 1 and with the lower member of the angling device shown in dotted-lines to the right 40 and left at forty-five degree angles; Fig. 3, an internal plan of one of the disk-members 45 of the several forming a part of each of the two swivel-joints seen in Figs. 1 and 2, but on a somewhat larger scale; Fig. 4, a transverse central section of one of the swivel-joints seen in Figs. 1 and 2, but on the same scale as that seen in Fig. 3; Fig. 5, a cross-section of the connected disk-members of adjacent pairs used in the angular-joint at the 50 top of the device; Fig. 6, a vertical section showing the lower end of the holder-tube, including its cap and the internal telescopic rod for sliding-extension and support of the lamp and, also, including the peculiar form 55 of spiral friction or torsional clench used on

said rod to sustain it within said tube at the desired longitudinal point; Fig. 7, a plan view of the preferred form of clamp used for securing the lamp in detachable position to the lower elbowed or angled end of said 60 rod; Fig. 8, a perspective view of one jaw-member of a modified form of said lamp-clamp; Fig. 9, a perspective view of the companion jaw-member of the said lamp-clamp seen in Fig. 8, and Fig. 10, a detail 65 fragmentary portion of said rod showing the spiral friction or clench thereon.

In these views, 1 indicates a tube, 2 a rod telescopically-sliding within said tube and 3 a cap having screw-threaded engagement 70 with the lower or outer end of said tube. The rod 2 engages a central opening in the cap 3 and is provided with a head or flanged upper end 4. A short tube or sleeve 5 surrounds the upper end of the rod 2 beneath the head 4 and a washer 6 is placed on said rod beneath the sleeve 5 and contacts with the lower or outer end of the tube 1, all as best seen in Fig. 6.

A clinging spiral or elastic wire 7 is 80 wound upon the rod 2 within the chamber 8 between the cap 3 and the washer 6. This spiral 7 has clenching or torsional engagement with the rod 2 and thereby forms a friction within the chamber 8 for supporting and sustaining said rod 2 at any desired longitudinal point within the tube 1 and is an important feature of my invention herein, both for its cheapness and efficiency without danger of displacement or being easily 90 broken.

The lower or outer end of the rod 2 is 95 preferably bent at a right-angle to form the arm 9 for the attachment of the lamp 10. Clamping-jaws intervene between the arm 9 and the lamp 10 and are made up of a pair of members 11 and 12. Said clamping-jaws 100 11 and 12 are preferably made as shown in Figs. 1 and 7, wherein they are shown as forking from a two-part arm or extension 13 and have spaced outer ends 14, 14, the latter being held together by a swinging link or ring 15 when the clamp is in engagement over the socket of the lamp. The ring 15 is swung from one of the arms 14 and 105 engages notches 16 arranged at different ascending elevations along the outer edge of the other one of said arms 14, to provide for different-sized lamps having varying diameters of sockets. This ring and ascending- 110

notch construction of closure for the jaws is a very convenient one and, also, a very effective one. The two-part arm or extension 13 forms a shank for the clamping-jaws and is 5 adapted for engagement over the arm 9 at the outer end of the rod 2, a bolt or screw 17 being used to secure the clamp in the desired position on said arm 9 whereby the lamp may be held at any angle around said 10 arm 9. The rod 2 being adapted to be rotated within the tube 1, the lamp at the lower end of the rod can thereby be further turned around throughout the circle of which the rod is the axial center. Thus a 15 practically universal joint is provided on the said rod itself and is an important feature herein.

The modified form of clamping-jaws seen in Figs. 8 and 9 is composed of two independent corresponding members 11 and 12, but the two-part arm or extension 13 and the clamp-arms 14 are omitted, the said extension 13 being replaced by a pair of arms 11^a and 12^a on the jaw-members 11 and 12, 20 respectively, each of such arms 11^a and 12^a having corresponding pendent semi-circular extensions 11^b and 12^b, respectively, the extensions 11^b and 12^b being adapted for engagement over the angled-arm 9 at the outer 25 end of the rod 2 and a suitable bolt or screw used, with its shank passing through the smooth bore of an opening 12^c made in the part 12^a of jaw-member 12 and engaging the threaded opening 11^c in the part 11^a of jaw- 30 member 11. Said last-named screw (not shown) holds the jaw-members 11 and 12 firmly in place on the angled-arm 9 when set in the desired position for use and it can be readily released in order to reset the 35 clamping-jaws for arranging the lamp supported thereby at the desired angle around said angled-arm 9. The jaw-members 11 and 12 of Fig. 6 are somewhat resilient, while those of Figs. 8 and 9 are not, the 40 resilience of the former being provided for in the use of the ring 15 in the closure thereof over the lamp-socket.

The lamp is provided with a conductor-cord 10^a of a length to suit the telescopic 45 sliding-extension of the rod 2 within the tube 1 and the slack in said conductor-cord is taken up by a spiral-spring 10^b, as best seen in Fig. 1, such spiral-spring having a hook 10^c at its lower end, over which hook 50 the cord engages, and the tendency of the said spring, in its expansive and contractive actions, being to operate automatically in the said take-up of the slack and letting out such slack in the lamp-cord. This lamp-cord 55 take-up device is also another important feature herein.

A series of pairs of disk-members are attached to the top or upper end of the tube 1, each pair being composed of circular disks 60 18 and 19 pivotally-held together at the cen-

ter by a transverse bolt 20. The members 18 and 19 of adjacent pairs of disks are arranged at right-angles to each other and integrally-connected together by means of an angular ligament 21, as best seen in Figs. 70 1 and 2, the other companion-members of the pairs of disks being independent ones and removable from place so that the interior of the pairs of disks are accessible for the purpose of placing lubricant in a somewhat 75 plastic or congealed form in the chamber 22 provided by the circular internal grooves and dishings or depressions made in the said disks, as best seen in Fig. 4. The said grooves and depressions allow for an outer 80 edge of sufficient width to furnish the required frictional-contact between the disks, and the centers do not touch each other so that the desired elasticity is effected in the disks and there is no possible impingement 85 of the two inner faces of the disks at the centers thereof whatever, thereby presenting the maximum of friction for the least amount of central bearing-surface. A turn-table or flange 23 is provided on the disk-member 18 of the upper pair and a bolt or screw 24 is used to attach it in place on the supporting-bar 25 or other object from 90 which the lamp is to be suspended. It is obvious that more than two companion pairs of the disk-members can be provided if desired, but the two pairs of disk-members set at right-angles to each other as shown will 95 furnish the required angling scope to which the lamp is to be ordinarily put in use. 100

I claim:-

1. In an incandescent electric-lamp holder, a tube, a rod telescopically sliding within said tube and having a flanged head at its inner end, a sleeve on the rod beneath said flange within the tube, a washer on the rod below said sleeve, an orificed screw-threaded cap attached at the lower end of said tube and a wire spiral wound on said rod within the tube between said washer and the cap 110 and adapted to present a clinging friction device to sustain said rod within the tube at the desired point of extension.

2. In an incandescent electric-lamp holder, a tube, a rod telescopically sliding within 115 said tube and having an inner head, a sleeve within said tube beneath said headed rod, a washer on the rod, an orificed cap fitting the outer end of said tube, an angled-arm at the lower outer end of said rod, a spring-jawed 120 clamp having a two-part clamp engaging said angled-arm on the rod, a bolt or screw for holding said spring-jawed clamp at the desired angle on said angled-arm and a link or ring variably-engaging the closing ends 125 of said spring clamping-jaws over the shank of a lamp.

3. In an incandescent electric-lamp holder, a tube, a rod telescopically sliding within 130 said tube and having a flanged head at its

- inner end, a sleeve on the rod beneath said flanged head, an orificed friction-spiral on said rod, a cap fitting the outer end of said tube and through which said rod passes, a 5 pair of clamping-jaws at the outer end of said rod, an electric-lamp supported in said clamping-jaws, an electric conductor-cord leading from said lamp to the source of current supply, a spiral-spring freely mounted 10 on said tube with one end thereof attached to said tube and the other end thereof provided with a hook over which said lamp-cord engages and such spring forming a take-up device for the lamp-cord in its automatic expanding and contracting actions 15 thereby providing for the slack in the lamp-cord.
4. An incandescent electric-lamp holder comprising a tube, a lamp-rod adapted to telescopically-reciprocate within said tube, a pair of hinge-disks each having flat, contacting, inner marginal faces and from one 20
- of which said tube extends and the other one of which has an inner, central, orificed boss that is suitably spaced away from the inner face of the companion disk and, also, has a lubricant-holding groove or recess surrounding the said boss, and the first-named of which disks has a centrally-orificed countersunk inner face, and a central bolt connecting said disks in such a manner that the coinciding countersunk portions of both disks are duly alined and spaced from each other and said central boss of one disk spaced away from the inner face of the other disk, 25 and the said flat-faced marginal edges frictionally-held in resilient-contact for supporting the electric-lamp at the desired angle.
